S. ULLMANN, OF NORFOLK, VIRGINIA.

Letters Patent No. 86,260, dated January 26, 1869.

IMPROVEMENT IN TRUNKS.

The Schedule referred to in these Letters Patent and making part of the same

To all whom it may concern:

Be it known that I, S. ULLMANN, of Norfolk, in the county of Norfolk, and State of Virginia, have invented a new and useful Improvement in Trunks; and I do hereby declare that the following is a full, clear, and exact description thereof, which will enable others skilled in the art to make and use the same, reference being had to the accompanying drawings, forming part of this specification, in which—

Figure 1 represents a transverse sectional elevation of a trunk having my improvement, and

Figure 2 represents an edge view of one of the metallic strips.

Similar letters of reference indicate like parts.

This invention relates to an improvement in trunks, and has for its object to perfect the construction of the jointed metallic straps which are now in use for the purpose of holding the lid in an open position.

It consists in providing the metallic strap with a rule-joint, whereby many important advantages are gained, the most important of which is that the pivot of the joint is brought, when the lid is open, below a straight line drawn from the two points of connection of the strap with the trunk-body and lid, whereby the pressure of the lid forward serves to strengthen the joint and prevent the possibility of the lid closing.

I am aware that pins have been used for this purpose, inserted in the sides of the strap, but by their use projections are formed, upon which articles of clothing are constantly catching; and if these articles are thin, as light silks and lace, they are liable to be torn, and thereby destroyed. If, however, the articles of clothing are of firmer stuffs, the joint is liable to be pulled outward, in removing them from the trunk, and the lid closed. This result would be attended with great inconvenience, particularly in those trunks that are provided with a spring-lock, because, when once

locked, they require manipulation with the proper key in order to open them.

A represents the body of the trunk, and
B, the cover.

C represents the metallic strips which I propose to use in substitution of the straps as ordinarily used, pivoted to the body of the trunk, at a, and to the cover, at b, and provided with a rule-joint, at D. The pivot of the joint D being below the right line, between the pivots a and b, any tendency of the cover to fall down forward will spring the strips downward, thereby preventing them from doubling at the said joint, as they must necessarily do before the cover can fall.

In this respect my improved braces are much superior to the straps commonly used, and they are also much more reliable in preventing the cover from falling backward, as they are susceptible of being much more firmly secured to the parts, and are thereby less liable to break or become disconnected.

When it is desired to close the trunk, the joints D must be raised until the pivot rises above the said right line between the pivots a and b, when the weight of the cover will cause them to double up, and they will assume the position shown in red when the trunk is closed.

Having thus described my invention,
I claim as new, and desire to secure by Letters Patent—

As a new article of manufacture, the metallic trunk-strap C, when provided with the rule-joint, D, without projecting pins, as herein described, for the purpose specified.

S. ULLMANN.
